Attorney

UNITED STATES PATENT OFFICE.

ALBERT EKLUND, OF PENDLETON, OREGON.

FASTENING DEVICE.

1,320,848.

Specification of Letters Patent.

Patented Nov. 4, 1919.

Application filed July 28, 1919. Serial No. 313,917.

To all whom it may concern:

Be it known that I, ALBERT EKLUND, a citizen of the United States, residing at Pendleton, in the county of Umatilla and State of Oregon, have invented certain new and useful Improvements in Fastening Devices, of which the following is a specification, reference being had to the accompanying drawings.

10 This invention relates to certain improvements in fastening devices and has relation more particularly to a device of this general character especially designed and adapted for use in connection with a shoe lace, and 15 it is an object of the invention to provide a novel and improved fastener of this type comprising separable parts which may be effectively maintained assembled and whereby the assembled sections may be anchored 20 to a shoe.

The invention consists in the details of construction and in the combination and arrangement of the several parts of my improved fastening device whereby certain 25 important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawings, wherein:

Figure 1 is a fragmentary view in perspective of the upper portion of a shoe upper with a fastening device constructed in accordance with an embodiment of my 40 invention applied thereto.

Fig. 2 is a fragmentary vertical sectional view taken through my improved device as herein embodied and in applied position.

Fig. 3 is a view in perspective of one of 45 the members comprised in my improved device as herein embodied.

Fig. 4 is a view in perspective of a second member comprised in my improved device as herein disclosed.

50 As disclosed in the accompanying drawings, A denotes a shoe upper with which coacts a lace L preferably of a type as disclosed in my Patent No. 1,303,869, dated May 20, 1919.

55 My improved fastener F is adapted to coact with the free end portion of the lace

L whereby the same is held against displacement after the shoe has been properly tightened upon the foot of the wearer.

My improved fastener F as herein disclosed comprises two separable members and one of said members comprises a flat plate 1 continued at its upper end by a substantially right angular extension 2. The side margins of the extension 2 are provided with inwardly directed wings 3 underlying the extension 2. The wings 3 are also of a width less than the length of the extension 2 so that a space or slot 4 is provided for a purpose to be hereinafter more particularly referred to. The plate 1 is also provided substantially centrally thereof with an opening 6 through which extends an eyelet 7. The eyelet 7 is also adapted to be directed through the shoe upper A so that the plate 1 may be effectively clamped to said upper. The plate 1 is also preferably positioned adjacent the upper margin of the upper A inwardly thereof so that the extension 2 will overlie the upper edge of the upper A.

80 The second member of my improved fastener comprises a flat spring plate 8 provided at its upper end portion with an inwardly directed extension 9 adapted to be inserted between the extension 2 of the plate 1 and the wings 3. The outer or free end of the extension 9 is provided with an inwardly directed lip or flange 10 adapted to seat within the space or slot 4 whereby the two sections of the fastener are effectively 90 maintained in assembled relation.

The flat spring plate 8 overlies the outer surface of the upper A and is provided with an opening 11 substantially in register with the eyelet 7. The plate 8 is also of such 95 longitudinal curvature as to have its free or lower end portion bearing against the upper A but with its extremity outwardly directed to facilitate the passage of the lace L therebeneath.

100 After the lace L has been applied to the shoe upper A the free end portion of the lace is directed through the eyelet 7 and the opening 11 and then the lace is forced between the plate 8 so that the lace L, or 105 more particularly the upper or free end portion thereof, is effectively held against displacement.

From the foregoing description, it is thought to be obvious that a fastening device constructed in accordance with my invention is particularly well adapted for use

by reason of the convenience and facility with which it may be assembled and operated and it is also obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A fastener for a shoe lace comprising a plate adapted to overlie the inner face of a shoe upper, said plate being provided with an extension adapted to bridge the upper edge of the upper, said extension being provided at its opposite sides with inwardly directed wings underlying said extension, said wings being of a width less than the length of the extension, an eyelet securing said plate to the upper, a second plate overlying the outer face of the upper and provided

at one end with an extension insertible between the extension and wings of the first 25 named plate, the extremity of said second named extension being provided with a lip extending between the first named plate and the wings, said second named plate having an opening substantially in registry with 30 the eyelet.

2. In combination with a shoe upper, a lace fastener comprising a member substantially the form of an inverted **U** and straddling the upper marginal portion of 35 the shoe upper, an eyelet securing an arm of the **U**-shaped member to the upper, the second arm of the **U**-shaped member being provided with an opening substantially in 40 registry with the eyelet.

In testimony whereof I hereunto affix my signature.

ALBERT EKLUND.
